Specification for Design.

Patented May 11, 1920.

Application filed February 11, 1919. Serial No. 276,442. Term of patent 14 years.

To all whom it may concern:

Be it known that I, CHARLES HAMMER, a citizen of the United States, and a resident of Queens, in the county of Queens and State of New York, have invented a new, original, and ornamental Design for a Bottle-Cap, of which the following is a specification, reference being had to the accompanying drawing, forming part thereof.

Figure 1 is a view in perspective of the bottle cap.

Fig. 2 shows a horizontal cross section at the upper part of the cap, showing the polygonal arrangement of the side wall at this portion.

What I claim is:—

The ornamental design for a bottle cap, as shown.

CHARLES HAMMER.
